FORD L. SABIN, OF CLEVELAND HEIGHTS, OHIO, ASSIGNOR TO THE WELLMAN ENGINEERING COMPANY, OF CLEVELAND, OHIO, A CORPORATION OF OHIO

COKE OVEN DOOR HANDLING MACHINE

Application filed November 30, 1927. Serial No. 236,602.

This invention relates to improvements in coke oven door handling machines or the like and has reference particularly to means for operating the door hooks and latches, means for breaking the seal between the door and the door frame, means for retracting the door and means for swinging the door around into position over the supporting carriage so that the side and rear surfaces of the door may be readily accessible for cleaning and repair.

Doors for coke ovens are ordinarily sealed into the door frames with clay or other non-fusible material which becomes hard during the coking operation, sticks to the door and door frame, and renders quite difficult the separation of the door from its frame, when the charge of coke is ready to be pushed out of the oven. If a sufficient pull is exerted upon the door in a direction outward and substantially normal to the plane of the door there is considerable tendency to loosen the frame in the oven wall.

Most mechanisms for handling oven doors carry them straight outward until the door frame and oven wall are cleared. But in conventional apparatus of this type it is difficult to get behind the door in order to clean off the sealing clay or to make repairs.

One of the objects of the invention, therefore, is the provision of means for breaking the seal of the door progressively from the top downward by means of an outward pull upon the top of the door in advance of that upon the bottom, whereby little tendency toward loosening of the frame results, the outward pull being accompanied by a slight upward pull in order to clear the bottom of the door frame.

Another object is the provision of means which will enable the first rearward travel of the door carrier to perform the operation of breaking the seal.

Still another object is the provision of means which will cause the door to be spaced slightly from the bottom of the door frame, when the door is entering or leaving the oven.

A further object is the provision of means for carrying the door into a clear space above the platform of the handling machine where

it will be readily accessible to a workman on the platform for cleaning or repairing.

Other objects and features of novelty will appear as I proceed with the description of that embodiment of the invention which, for the purposes of the present application, I have illustrated in the accompanying drawings, in which—

Fig. 1 is a plan view of a door handling machine embodying the invention shown in operative relation to a door in an oven wall, the latter parts being in section.

Fig. 2 is an end elevation of the same machine, the oven wall and door being illustrated in vertical section;

Fig. 3 is a side elevation of the machine looking in the direction towards the oven; and

Fig. 4 is a view principally in vertical section showing the position of the door as it enters or leaves the oven, together with means for supporting it in that position.

In the drawings there is illustrated a carriage framework comprising side members 10 and 11 and end members 13 and 14, the members 11, 13 and 14 being made up of structural iron shapes while the member 10 is preferably a casting which is provided with an undercut portion, indicated by the dotted line 15, Fig. 3. The frame carries axles 16 upon which are mounted flanged wheels 17 that are adapted to run upon track rails 18. The framework supports a platform 19 that extends across the carriage at each end and along one side thereof, being cut away from the opposite side near the middle portion thereof, including the area over the undercut portion 15 of the side member 10. The track rails 18 are laid parallel with the front wall 20 of the oven, as is customary.

At one end of the carriage there is a superstructure 21 including uprights, rails and braces all connected together rigidly and supported upon and attached to the framework of the carriage in any suitable manner. This superstructure supports an upper bearing 22 for a vertical rock shaft 23, the lower bearing 24 of which is mounted in the frame of the carriage. A second rock shaft 25 is

also supported at the top in the superstructure 21 and at the bottom in the framework of the carriage. The shaft 23 has attached thereto upper and lower horizontal arms 26, while the shaft 25 carries arms 27 which may be formed integral if desired. The two lower arms 26 and 27 are in the same horizontal plane, a portion of the arm 27 being behind the arm 26, in Fig. 3. Hereinafter the arms 26 and 27 are sometimes referred to as links.

In order to swing the links 26, the shaft 23 may be supplied near its lower end with a spur gear 28, which is driven by a pinion 29 mounted on the lower end of a shaft 30 which is rotatably supported at its ends in the framework of the carriage and in the superstructure 21 thereof. The upper end of the shaft 30 carries a worm gear 31 that meshes with a worm 32 on the end of a shaft 33 driven by an electric motor 34. The latter may be supplied with a solenoid brake 35, if desired.

The door carrier is a rather narrow structure indicated, generally, by the numeral 36, and comprises brackets 37 to which the ends of links 26 and 27 are pivotally connected. The carrier is thus supported upon the links and moves as they move. The two brackets 30 for the links 27 are, of course, in vertical alignment and the same is true of the two brackets for the links 26. Hence, the vertical posture of the carrier is maintained in all of its positions.

The top of the carrier consists of a casting 38, which has a pair of forwardly projecting nose pieces 38' carrying the fulcrum 39 of a vertically arranged lever 40 having upper and lower door engaging projections 41 and 42 formed in bifurcations of the lever. At 43, near the upper end of the lever 40 and between said bifurcations, there is pivoted a bell crank 44, one arm of which constitutes a door hook for engagement beneath the projection 45 on the door 46. The other arm has an operating link 47 pivotally connected thereto. A lever 48 is pivotally connected at 49 to the lower end of lever 40 between the bifurcations thereof, and this lever 48 also constitutes a door hook for engagement with a projection 50 near the lower extremity of the door.

Latching bars 51 and 52 are mounted in vertical guides 53 and 54 on the door, being adapted to engage behind inclined retainers 55 fastened to reinforcing structural iron posts 56 on either side of the door opening. The lower or locking positions of the latch bars 51 and 52 are indicated in dotted lines at 51' and 52', respectively. Cooperating with the latch bars 51 and 52 are latch lifters 57 and 58 pivoted at 59 and 60 to the lever 40. The hook levers 44 and 48 and the latch-lifting levers 57 and 58 are all joined together for simultaneous movement by means of link

rods 61, 62 and 63, which are preferably of adjustable length.

The pivot 49 at the lower end of lever 40 is connected by a link 64 with the short arm of a bell crank lever 65 that is pivoted at 66 to the door carrier 36. The long arm of the lever 65 is pivotally attached to a rod 67 provided with a collar 68 that supports a weight 69 which has an axial opening for the rod 67. Above the weight 69 there is a coil spring 70 surrounding the rod 67 and adapted to engage against the bottom of a guide 71 for the rod, for the purpose of cushioning sudden upward impulses of the weight 69. Above the guide 70 the rod 67 has a second collar 72 and a second coil spring 73 whereby downward motion of the weight 69 is also cushioned. It will be obvious that the weight 69 tends to push the projection 42 on the lever 40 against the surface of the door 46.

Within a hollow part of the casting 38, on the top of the door carrier, I pivot the lower end of a lever 74, which is connected intermediate its ends with the above mentioned link 47 and which terminates at its upper end in a transverse bar 75 having trunnions 76 on the outer ends thereof. These trunnions pivotally support guide blocks 77 in which are formed slide guides for rods 78. The latter are fixed in blocks 79 which are pivotally mounted upon crank pins 80. Coil springs 82 surround the rods 78 pressing at one end against the blocks 77 and at the other end against abutments 81 carried by the blocks 79, the abutments 81 also having openings through which the rods 78 extend. The crank pins 80 are carried by cranks 82 mounted upon a shaft 83 extending through a gear casing 84, with which the shaft carries a worm gear 85 driven by a worm (not shown) on a shaft 86, which is joined by a flexible coupling 87 to the shaft of an electric motor 88 supported upon the casting 38. This motor also preferably has a solenoid brake 89.

It will be noted that the platform 19 affords a clear passage along one side of the carriage and a clear space at one end thereof opposite the full open position of the door, so that there is ample room for cleaning the sealing clay from the door or for repairing the same. I preferably provide a heat shield 90 along one side of the carriage to protect the workmen upon the carriage from the heat of coke discharged below the track 18.

Operation: When it is desired to remove the door from any given retort, the carriage with the door carrier in retracted position thereon is moved along the rails 18 by any suitable means to the proper position, when the motor 34 is set in motion to drive worm 32 and worm gear 31, whereby shaft 30 is rotated, turning pinion 29 and gear 28 meshing therewith. By this means rock shaft 23

is moved at a relatively slow pace to swing links 26 from the dotted line position of Fig. 1 towards the full line position thereof. This movement causes links 27, turning with or upon shaft 25, to swing also, thereby helping to direct the course of movement of the door carrier 36. The links 27 may well be termed followers, since they are not power actuated. At this time the lever 40 stands at the angle shown in Fig. 4, but the hook levers 44 and 48 and the latch lifting levers 57 and 58 are in a lowered position.

As the lever 40 approaches the door the projections 42 are first to engage the door. Continued forward movement of the carrier then causes the lever 40 to swing upon its fulcrum 39 into the position illustrated in Fig. 2, where the projections 41 also engage the door. At this time the latch bars 51 and 52 are in the dotted line positions 51' and 52', and the latch lifters 57 and 58 are in their lower position below the bars 51 and 52. The hooks 44 and 48 are also in their lower position out of engagement with the projections 45 and 50 of the door. The crank pins 80 are at this time in positions to the rear of that illustrated and the lever 74 is consequently swung back. The motor 88 is now started and the crank pins 80 are advanced slowly, swinging the lever 74 forwardly, this motion being transmitted through link 47 to the lower arm of the bell crank lever 44. The upper or hook arm of the lever 44 is thereby swung upwardly until it engages the projection 45 on the door. At the same time, through link rods 61, 62 and 63, the lower hook 48 is swung up into the position illustrated in Fig. 2 and the latch lifters 57 and 58 are also swung up, moving the latch bars 51 and 52 into their full line position where they are above the retainers 55. The door is thus unlatched and the hooks 44 and 48 are in position to lift it. If the operator should permit the motor 88 to run after the door hooks are in engagement with the projections 45 and 50, no harm results because the springs 82 are then compressed to take the increased load off the door hooks. This compression may continue to a point where the crank pins 80 cross the line between the shaft 83 and the trunnions 76, when further operation of the motor in the same direction, of course, gradually relieves the pressure upon the springs. Motor operation of the hooks 44 and 48 and of the latch lifters 57 and 58 is not essential, as the operation of these parts may be manual, if preferred.

Now the operator starts the motor 34 in a direction to swing the arms 26 toward the rear, moving the door carrier in a direction substantially straight outward for a time. During the first part of this movement the lower end of lever 40 holds the lower part of the door in engagement with its seat, this effect being secured by means of the weight

69. This causes the lever 40 to swing upon its fulcrum 39. The rear end of link 47 is maintained in a fixed position, with respect to the carrier, and as a consequence of this fact and of the backward movement of pivot 43 the bell crank 44 swings upon the pivot 43 exerting an upward force upon the projection 45. This shifts the door into the position illustrated in Fig. 4. The operation of motor 34 is continued and the door carrier is retracted, moving outwardly first in a substantially straight line until the door frame is entirely cleared and thereafter in a curved path. The path of one forward edge of the door is indicated by the dotted line A in Fig. 1. In the same figure the path of a rear corner of the casting 38 is indicated by the dotted line B. This line sweeps over the side portion of the platform 19 but is well above the head of a man standing thereon. The path of that portion of the door carrier below the casting 38 which moves furthest to the rear is indicated by the dotted line C. It will thus be seen that the carrier never interferes with the movements of a workman upon the platform.

After the door has reached the dotted line position of Fig. 1 the carriage is moved along away from the open retort and the charge of coke is pushed out. Workmen then clean the sealing clay away from the door and door frame. Then the carriage is again brought into a position in front of the oven and the motor 34 operated to move the door carrier toward the door frame. The lower end of the door first enters the frame until it makes engagement with the sides of the frame. Continued inward movement causes the lever 40 to swing from the position in Fig. 4 toward that of Fig. 2, the weight 69 being thereby elevated, until the parts all assume the positions shown in Fig. 2. Then the motor 88 is again operated to retract the link 47, swinging the hook levers 44 and 48 and the latch lifters 57 and 58 downwardly to unhook the door and latch it, when the carrier may be moved away and the sealing clay applied.

In pushing the door into position in its frame, it would, of course, be possible to apply too great a pressure so that damage to the door or door frame might result. To obviate this difficulty a limit switch to stop the action of motor 34 at a predetermined point may be employed or a slip connection may be used in the gearing between the motor 34 and the rock shaft 23. Both of these expedients, being well known in the art, they are not herein illustrated.

The use of the hook 48 at the bottom of the door, although preferred, is not essential, as the single hook 44 may be employed instead. The arrangement of the pivot points 39 and 43 may be varied or even inverted, and the shape of lever 44 as well as the means for operating it may also be modified consider-

ably. But the swinging of the lever 40 at the beginning of the rearward movement of the door carrier to bring about a lifting of the door and a breaking of the seal thereof is an important feature of the invention without regard to the details of construction employed. The supporting and swinging of the door carrier upon links is also an important feature, having the advantage of putting the door into a desirable position upon the carriage and having the further advantage of a low center of gravity as compared with most other mechanisms of this kind.

Having thus described my invention, what I claim is:

1. In a door handling machine for coke ovens or the like, a carriage adapted to be positioned opposite the front wall of an oven, a door carrier on said carriage adapted to move towards and away from the oven, a vertical lever pivoted above its lower end at the forward end of said carrier, a door hook pivotally mounted on said lever, means for bringing said hook into engagement with a projection on the door, and means for holding the lower end of said lever against the door during the first part of the rearward movement of the carrier, whereby said rearward movement swings said vertical lever and raises said door hook.

2. In a door handling machine for coke ovens or the like, a carriage adapted to be positioned opposite the front wall of an oven, a door carrier on said carriage adapted to move towards and away from the oven, a vertical lever pivoted above its lower end on said carrier at the forward end thereof, a door hook pivotally mounted on said lever, means on said carrier for bringing said hook into engagement with a projection on the door, and means for holding the lower end of said lever against the door during the first part of the rearward movement of the carrier, whereby said rearward movement swings said vertical lever and raises said door hook.

3. In a door handling machine for coke ovens or the like, a carriage adapted to be positioned opposite the front wall of an oven, a door carrier on said carriage adapted to move towards and away from the oven, a vertical lever fulcrumed above its lower end on said carrier at the forward end thereof, a door hook pivotally connected at spaced points with said lever and with said carrier respectively extending forwardly and adapted to engage beneath a projection on the door, and means for urging the lower end of the lever forward against the door, whereby the rearward movement of the carrier will swing the lever about its fulcrum and the hook about its pivotal connection with the lever to raise said hook.

4. In a door handling machine for coke ovens or the like, a carriage adapted to be

positioned opposite the front wall of an oven, a door carrier on said carriage adapted to move towards and away from the oven, a vertical lever fulcrumed on said carrier near the upper and forward portion thereof, a door hook on said lever near the upper end thereof extending forwardly therefrom and adapted to engage beneath a projection on the door, said lever extending downwardly to a position near the lower end of the door, and means for urging the lower end of the lever forward against the door, whereby the rearward movement of the carrier will swing the lever about its fulcrum to raise said hook.

5. In a door handling machine for coke ovens or the like, a carriage adapted to be positioned opposite the front wall of an oven, a door carrier on said carriage adapted to move towards and away from the oven, a vertical lever fulcrumed on said carrier at the front end thereof, a door hook pivotally mounted on said lever and adapted to engage beneath a projection on the door, a link having one end connected with said hook, means for holding the other end of said link in a fixed position on the carrier, and means for urging the lower end of the lever forward against the door whereby the rearward movement of the carrier will swing the lever about its fulcrum to raise said hook.

6. In a door handling machine for coke ovens or the like, a carriage adapted to be positioned opposite the front wall of an oven, a door carrier on said carriage adapted to move towards and away from the oven, a vertical lever fulcrumed on said carrier at the forward end thereof, a door hook on said lever extending forwardly therefrom and adapted to engage beneath a projection on the door, a latch lifter also mounted on said lever, means for actuating said hook and lifter simultaneously to lift the latch to inoperative position and raise the hook to operative position, and means set in motion by the rearward movement of the carrier for swinging said lever upon its fulcrum first to raise said hook further and thereby lift the door, and then to tilt the upper end of the door outwardly.

7. In a door handling machine for coke ovens or the like, a door carriage adapted to be moved toward and away from an oven, a lever pivoted on said carriage with unequal moment arms, a door hook pivotally connected at spaced points with said carriage and the short arm of said lever, whereby the rearward movement of said carriage will swing the lever about its pivot and the door hook about its pivotal connection with said lever to raise said hook when it is in engagement with said door.

In testimony whereof, I hereunto affix my signature.

FORD L. SABIN.
